BLANKET FASTENER

Moses Liebmann, New York, N. Y.

Application April 17, 1940, Serial No. 330,030

2 Claims. (Cl. 24—72.5)

This invention relates to clamping means for holding blankets, sheets and bedclothes in place against a mattress, examples of such devices being shown in my prior Patents Nos. 2,149,971 and 2,195,967. One of the objects of the present invention is to provide a device which will effectually prevent the bedclothes from being kicked or thrown off the bed or otherwise displaced, thus leaving the body exposed and unprotected.

In the devices disclosed in my patents above mentioned, spring means is employed for exerting clamping force upon a pair of jaws which clamp the blanket around the rolled edge of the mattress. In order to apply sufficient clamping force to enable the blanket to be securely held in place to resist the pulling strains imposed upon it by movements of a person in bed, the springs employed had to exert considerable force, with the result that the manual strength required to spread the jaws apart against the tension of the springs when placing the device in position or removing it, was considerable. It is therefore the primary object of the present invention to provide a clamp in which springs are not required for the purpose of applying clamping force, but are instead used for assisting in spreading the jaws apart or opening the device, and means are employed for positively moving the jaws into clamping position and enabling a requisite and selected amount of clamping force to be exerted without the exercise of any great manual strength on the part of the person placing the clamp in operative position.

More particularly, the invention comprises the employment of a pair of jaws, hinged or otherwise movably associated or connected, said jaws being of such shape that the same co-operate in embracing and fitting over the rolled edge of a mattress and one or more blankets extending over the same, and in the provision of a spring so disposed in respect to the jaws that it tends to spread the jaws apart, and in the further provision of a bolt or other clamping element which is operative, upon manual adjustment, to move the jaws into clamping position with a selected amount of clamping force applied between the jaws on the blanket and rolled edge of the mattress.

In the accompanying drawing, wherein an embodiment of the invention is disclosed, Fig. 1 is a plan view of a fastener or clamp made in accordance with the invention; Fig. 2 is a side view of the same; Fig. 3 is a rear view of the device; and Fig. 4 is a sectional view through

a part of a mattress and superposed blanket, showing the application of the clamp thereto.

With reference to the structure shown in Fig. 4, 13 indicates the rolled edge of a mattress, said rolled edge being usually formed along the top of the mattress and it extends completely around the same. Superposed upon the mattress in the conventional way is a blanket, sheet, quilt or other bedclothing indicated at 14 which may be securely and neatly held in position over the mattress by a plurality of clamping devices, one of which is shown in the drawing.

The clamping device consists of a pair of like jaws 1 and 2 curved toward one another as at 15 at one end and hinged together as indicated at 6, or in any other equivalent manner. The jaw 1 has a curved or arcuate portion 3, and the opposed jaw 2 has a similarly shaped part 4. These arcuate portions 3 and 4 of the jaws co-operate in embracing and snugly fitting over the rolled edge of the mattress and the blanket extending thereover, as clearly shown in Fig. 4. Each jaw has its forward end provided with an outwardly extended flange 11 which grips the blanket securely, yet without cutting into or tearing the same.

The means for adjusting the position of the jaws relative to one another is located adjacent to the rear hinged ends of the jaws, said means consisting of the bolt 8, which extends through the apertures 7 in the jaws, said bolt being located in the flat portions 5 of the jaws and between the arcuate portions of the jaws and the hinged connection 6, between said jaws. Surrounding the bolt 8 is a spring 9 which is located between the jaws and tends to normally spread the same apart or separate them. An adjusting nut 10 is received on the threaded portion of the bolt at the outside of the jaw 2, said nut being rotative on the bolt to compress the spring and draw the jaws toward one another and bring them into clamping co-operation with the requisite amount of clamping force required to securely hold the blanket over the rolled edge of the mattress.

Briefly, the operation of the device is as follows:

In applying the clamp in position the nut 10 is rotated to enable the jaws to be spread apart under the impulse of the spring 9 for the requisite amount to enable the clamp to be fitted over the rolled top of the mattress and the blanket 14 or other bedclothing extended thereover. By then turning the nut 10 to advance it toward the jaws, it will move the same toward one another until 55

the proper amount of clamping force is applied to hold the blanket securely against displacement. Another simple manner of speedily applying the clamp is to squeeze the jaws together between 5 the fingers of one hand while the rolled edge of the mattress and blanket thereover is disposed between the jaws, and then, while holding the jaws in gripping position, twirl the nut with the fingers of the other hand until it holds the jaws in the 10 manually-set position of clamping. Since the spring 9 tends to spread the jaws apart automatically upon retractive movement on the nut 10 on the bolt 8, the release of the device from clamping position is effected by merely turning 15 the nut to cause it to move outwardly along the bolt. It will thus be apparent that the placement and removal of the device is simply and easily done; that the imposition of manual strength in removing the clamp is unnecessary and that a 20 regulatable amount of clamping pressure is easily attained by merely adjusting the nut 10 on the bolt 8.

What I claim is:

1. A device for holding bed clothing to the 25 rolled edge of a mattress comprising, a pair of jaws hinged together at one of their ends and movable toward one another and adapted to grip the rolled edge of the mattress between them, each of said jaws including a portion arcuately 30 curved to fit the curvature of the rolled top of the mattress, the jaws being apertured at a point remote from the curved portions and between

their curved portions and the hinge, the hinge consisting of interfitting rolled parts at the ends of the flat portions of the jaws, with a pintle extending through said rolled parts, an adjusting bolt extending through the apertures in the jaws, said bolt being provided on the outside of one of the jaws with a nut for adjusting the jaws toward one another, and a spring surrounding the bolt between the jaws and tending to spread the jaws apart. 5

2. A device for holding bed clothing to the rolled edge of a mattress comprising, a pair of jaws hinged together at one of their ends and movable toward one another and adapted to grip the rolled edge of the mattress between them, 10 each of said jaws including a portion arcuately curved to fit the curvature of the rolled top of the mattress, said portion having an angular free end, and including also a flat portion disposed between the curved portion and the hinge, the hinge consisting of interfitting rolled parts at the ends of the flat portions of the jaws, with a pintle extending through said rolled parts, the flat portions of the jaws being apertured, an adjusting bolt extending through the apertures in the jaws, 15 said bolt being provided on the outside of one of the jaws with a nut for adjusting the jaws toward one another, and a spring surrounding the bolt between the jaws and tending to spread the jaws apart. 20
